US00D862509S

(12) **United States Design Patent** (10) **Patent No.:** **US D862,509 S**
 Lewis et al. (45) **Date of Patent:** **** Oct. 8, 2019**

(54) **DISPLAY SCREEN OR PORTION THEREOF HAVING A GRAPHICAL USER INTERFACE**

(71) Applicant: **Amazon Technologies, Inc.**, Seattle, WA (US)

(72) Inventors: **Kimberly Anne Lewis**, Seattle, WA (US); **Elliot Dickison**, Shoreline, WA (US); **Dan Griffin Dilworth**, San Diego, CA (US); **Michael Keith Lemmon**, Seattle, WA (US); **Carson Scott Reid**, Seattle, WA (US)

(73) Assignee: **Amazon Technologies, Inc.**, Seattle, WA (US)

(**) Term: **15 Years**

(21) Appl. No.: **29/614,838**

(22) Filed: **Aug. 23, 2017**

(51) LOC (12) Cl. **14-04**

(52) U.S. Cl.

USPC **D14/488**

CLAIM

The ornamental design for a display screen or portion thereof having a graphical user interface, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a front view of a first embodiment of a display screen or portion thereof having a graphical user interface. FIG. 2 is a front view of a second embodiment of the display screen or portion thereof having a graphical user interface; and,

FIG. 3 is a front view of a third embodiment of a display screen or portion thereof having a graphical user interface. The dashed broken lines depict portions of the display screen or portion thereof having a graphical user interface that form no part of the claimed design. The dot-dashed broken lines showing portions of the display screen or portion thereof form no part of the claimed design.

1 Claim, 3 Drawing Sheets
